United States Patent Office.

HARRISON EATON, OF AMHERST, NEW HAMPSHIRE.

Design No. 3,304, dated January 5, 1869.

DESIGN FOR A STOVE.

The Schedule referred to in these Letters Patent and making part of the same.

To all persons to whom these presents may come:

Be it known that I, HARRISON EATON, of Amherst, in the county of Hillsborough, and State of New Hampshire, have invented or produced a new Ornamental Design for a Stove; and I do hereby declare the same to be fully described in the following specification and represented in the accompanying drawings, of which—

Figure 1 is a perspective elevation of the stove, the same exhibiting the top, front end, hearth, one side, and three of the legs.

Figure 2 is a perspective elevation, exhibiting the rear end, the other side, the top, and three of the legs.

In this design each of the sides of the stove has two duplex panels in *bas-relief*, each being composed of one rectangular base-panel, A, and two pointed-arch panels, B B, raised in relief on the base-panel. The edges of each of the panels are moulded or formed with mouldings.

The back of the stove has a single plane panel in *bas-relief*, C. The said panel, as well as each of the base-panels of the duplex panels of the sides, springs

from a recessed panel, whose edges are bounded by mouldings.

The top of the stove is in two halves or parts, D E, hinged together, so that the front portion may be turned up at a right angle to the back part, the hinges a a being provided with stops, b b, to support in an upright position the movable top. The object of this formation of the top is to enable the fire-place of the stove to be fed with wood.

There is a kettle-opening in such movable part E, it being provided with a cover, c.

The hearth, bottom, and top plates of the stove are made with mouldings on their edges. The corners are round, and the legs are ornamented, as represented.

A tubular pipe-neck, d, opens through the part D of the top, and is erected thereon.

I claim the design, substantially as represented and described.

HARRISON EATON.
